CLAIM

I claim the ornamental design for a trading card display system, as shown.

DESCRIPTION

FIG. 1 is a perspective view of a trading card display system with individual card storing components;

FIG. 2 is a front elevational view thereof;

FIG. 3 is a top plan view thereof;

FIG. 4 is a bottom plan view thereof;

FIG. 5 is a left side view thereof;

FIG. 6 is a right side view thereof; and,

FIG. 7 is a front elevational view of a second embodiment of a trading card display system with individual card storing components.
